DESIGN FOR A GOLF BALL OR THE LIKE

Henry K. B. Davis, Springfield, Mass.

Application February 20, 1936, Serial No. 61,261

Term of patent 14 years

To all whom it may concern:

Be it known that I, Henry K. B. Davis, a citizen of the United States, residing at Springfield, in the county of Hampden and State of Massachusetts, have invented a new, original, and ornamental Design for Golf Balls or the like, of which the following is a specification, reference being had to the accompanying drawing, forming part hereof:

Fig. 1 is a face view of one side of a golf ball or the like embodying my new design.

Fig. 2 is a fragmentary detail view taken on lines 2—2 of Fig. 1; and

Fig. 3 is a sectional view on the line 3—3 of Fig. 2 to more clearly disclose certain features of the design.

The design consists of six similar panels one on each of six sides of the ball. The panel shown on the face of the ball in Fig. 1 is repeated on the opposite face of the ball and on the top, bottom and side faces adjacent thereto.

I claim:

The ornamental design for a golf ball or the like substantially as shown and described.

HENRY K. B. DAVIS.
